CLAIM

An ornamental design for an indicator display, as shown and described.

DESCRIPTION

FIG. 1 is a front perspective view of the first embodiment of an indicator display, shown in an environment of use.

FIG. 2 is a perspective view of the indicator display of FIG. 1.

FIG. 3 is a rear view of the indicator display of FIG. 1.

FIG. 4 is a side view of the indicator display of FIG. 1.

FIG. 5 is a top view of the indicator display of FIG. 1.

FIG. 6 is a bottom view of the indicator display of FIG. 1.

FIG. 7 is a perspective view of the second embodiment of an indicator display.

FIG. 8 is a front view of the indicator display of FIG. 7.

FIG. 9 is a side view of the indicator display of FIG. 7.

FIG. 10 is a top view of the indicator display of FIG. 7.

FIG. 11 is a bottom view of the indicator display of FIG. 7.

FIG. 12 is a perspective view of the third embodiment of an indicator display.

FIG. 13 is a front view of the indicator display of FIG. 12.

FIG. 14 is a side view of the indicator display of FIG. 12.

FIG. 15 is a top view of the indicator display of FIG. 12; and,

FIG. 16 is a bottom view of the indicator display of FIG. 12.

The elements shown in broken lines, which are depicted as dot-dot-dot lines, are directed to environment and for illustrative purposes only and do not form part of the claimed design. Further, the dot-dash line(s) define the bounds of the claimed design and form no part thereof.
